Primary Examiner — Ruth McInroy(74) *Attorney, Agent, or Firm* — Grossman Tucker
Perreault & Pfleger, PLLC(57) **CLAIM**

The ornamental design for a vacuum cleaner head, as shown and described.

DESCRIPTION

FIG. 1 is a perspective view of a vacuum cleaner head showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a perspective view thereof, showing the vacuum cleaner head in use with broken line environmental structure.

FIG. 8 is a front elevational view of FIG. 7;

FIG. 9 is a rear elevational view of FIG. 7;

FIG. 10 is a left side elevational view of FIG. 7;

FIG. 11 is a right side elevational view of FIG. 7; and,

FIG. 12 is a top plan view of FIG. 7.

The broken lines in the drawings are for illustrative purposes only and form no part of the claimed design.
